INVENTOR.

Joseph Klubnick

UNITED STATES PATENT OFFICE.

JOSEPH KLUBNICK, OF BRIDGEPORT, CONNECTICUT.

EXERCISER.

Application filed May 10, 1923. Serial No. 637,999.

To all whom it may concern:

Be it known that I, JOSEPH KLUBNICK, a citizen of the United States, residing at Bridgeport, county of Fairfield, State of Connecticut, have invented a new and useful 5 Exerciser, of which the following is a specification.

This invention has for its object to produce a simple and inexpensive exercising 10 device that will be durable and practically impossible to get out of repair, that will cause exercise of a maximum number of body, leg, and arm muscles simultaneously, that will be equally well adapted as an exerciser for men and women either young or 15 old, and will be especially adapted for use by children as a plaything, and by athletes, boxers, and wrestlers as a mild and light training device on account of the resemblance of its use to that of a skipping rope.

With the above and other objects in view, I have devised the novel exerciser which I will now describe referring to the accompanying drawing forming part of this specification and using reference characters to indicate the several parts.

Fig. 1 is an inverted plan view corresponding with Fig. 2, and

Fig. 2 is a side elevation of the exerciser complete, the handle and arm being partly broken away to illustrate details of construction.

10 denotes the handle, 11 the swinging arm, and 12 a link by which the arm is connected to the handle in such a manner as to permit the arm, while extending radially from the handle, to be swung bodily about the handle when the latter is itself moved in a curved, more or less elliptical, path.

The handle is preferably made in two or more parts which may be detachably connected together in any suitable manner so as to permit packing the device when not in use or for shipment in the smallest space possible. In the present instance, I have shown the handle as made in two parts which are connected together by a threaded joint, as at 13. The specific shape or configuration of the handle and arm are both immaterial so far as the present invention is concerned. The handle may be made of wood or metal, or, wood and metal, as preferred.

55 The arm may be made in whole or in part

of soft rubber so-called, that is, rubber having approximately the hardness of a pencil eraser. In the outer end of the arm I preferably provide a hole 14 in order to still further soften the end of the arm and consequently minimize the blow should it accidentally strike the leg of the user.

The handle and arm are connected together in any suitable manner so as to permit the arm to be swung bodily about the handle as will be more fully explained. In the present instance, I have shown the handle and arm as connected together by means of a metallic double link 12. The lower end of the handle is shown as provided with a rounded head 16 above which is a neck 17 which is loosely enclosed by one eye of the double link. The arm is shown as provided at its inner end with an eye 18 which is loosely engaged by the other eye of the double link, that is, the eye not engaging the handle.

The operation is to cause the arm to swing about the handle by centrifugal force, in substantially the horizontal plane, and to skip over it somewhat as in using a skipping rope. The exercise may be made relatively easy and gentle or relatively difficult and strenuous. The higher the plane in which the arm is caused to swing and the greater the speed at which it is caused to swing, the more difficult and strenuous the exercise. The arm may be swung in either direction and high and fast, or low and slow depending upon the skill and age of the user. The user may skip over the arm with one leg as long as desirable or practicable and then repeat the operation with the other leg, or an athletic person, skilled in the use of the exerciser, may jump over the arm while it is swung in either direction under both feet.

Having thus described my invention, what I claim is:

1. An exerciser comprising a handle, an arm made of relatively soft rubber, and a link loosely connected to the arm and handle and adapted to rotate about the axis of the handle.

2. An exerciser comprising a handle having a head and above the head a neck, an arm having at one end an eye, and a double link, one eye of which engages the eye of the arm, the other eye of the link loosely embracing the neck of the handle to allow

the arm to swing in a circle about the handle in a plane substantially at right angles to the axis of the handle.

3. An exerciser comprising a handle made in two parts, detachably connected, and having a head and above the head a neck, an arm having at one end an eye, and a link having an eye engaging the eye of the arm and an eye loosely embracing the neck of the handle to allow the arm to swing in a circle about the handle in a plane substantially at right angles to the axis of the handle.

4. An exerciser comprising a handle, a rubber arm having at one end a hole and at the other end an eye, and a link engaging the eye and adapted to turn freely on the handle to allow the arm to swing in a circle about the handle in a plane at substantially right angles to the axis of the handle. ¹⁵

In testimony whereof I affix my signature.
JOSEPH KLUBNICK.
